Primary Examiner — Kevin Rudzinski*Assistant Examiner* — Sean D Lough(74) *Attorney, Agent, or Firm* — Heslin Rothenberg Farley & Mesiti P.C.(57) **CLAIM**

The ornamental design for a controller dock, as shown and described.

DESCRIPTION

FIG. 1 is a top front perspective view for a controller dock showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrated within the bounds of the claimed design in FIGS. 1 through 7 have been shown for the purpose of illustrating a portion of the controller dock that forms no part of the claimed design.

1 Claim, 7 Drawing Sheets(56)
